UNITED STATES PATENT OFFICE.

JOHN E. FEFEL, OF BRIDGEPORT, CONNECTICUT, ASSIGNOR OF ONE-HALF TO FRANK J. HOEY, OF NEW YORK, N. Y.

FABRIC-WEAVING MACHINE.

Application filed May 29, 1926. Serial No. 112,505.

My invention relates to improvements in fabric weaving machines and has for its object to provide a machine of this type, preferably adapted for weaving a narrow ribbed bon-like fabric—as tape, braid, and the like. A specific object of the invention is to provide a fabric-weaving machine adapted for weaving fabric like that disclosed and claimed in my co-pending application, Serial No. 98,066, filed March 29, 1926, and in which a reinforced selvage is provided at each longitudinal edge.

It is the purpose of my present invention to provide a novel means for handling the 15 weft or filling threads in a fabric without the use of a bobbin, shuttle, or the like, and to employ in their stead needles of novel construction and arrangement which are associated to cooperate in a way to successively lay the weft threads in the warp, and, further, to provide needle and looper means 20 for looping selvage threads in relation to the edge portions of the weft whereby a selvage is formed of the same structure and strength 25 at each side of the fabric.

I have further shown means and mechanisms for operating these weft and selvage thread-handling needle and looper means, but which obviously may be varied some- 30 what in their arrangement or detail of construction and are, therefore, subject to such changes as may be necessary, and permissible within the scope and breadth of the claims to follow.

35 By the use of the needle and looper means as applied and operated in my invention, I am able to take the filling and selvage threads directly from the source—as, for instance, a spool—thereby eliminating the 40 labor involved in winding this vast amount of material upon bobbins, as is customary with the old style of weaving machines, thereby saving a great amount of floor space 45 as is now required for this preliminary work.

With the above and other objects in view, an embodiment of the invention is shown in the accompanying three sheets of drawings, and this embodiment will be hereinafter 50 more fully described with reference thereto, and the invention will be finally pointed out in the claims.

In the drawings forming a part of this specification:

Fig. 1 shows a front elevation of a fabric-weaving machine, according to the present embodiment of the invention. 55

Fig. 2 is an edge view as seen from the right of Fig. 1.

Fig. 3 is an enlarged sectional view 60 through the rack and pinion mechanism, taken on line 3 of Fig. 2.

Fig. 4 shows a plan view of a sample of fabric woven by my improved machine.

Figs. 5, 6, 7, and 8 are front and plan 65 diagrammatic views respectively, showing steps in the fabric weaving operations of the needles and cooperating loopers carried in the frame members of the weaving machine. 70

Fig. 9 is a detail sectional view on the line 9—9 of Fig. 8.

Figs. 10 and 11 are plan views showing further steps; and

Fig. 12 is a detail sectional view on the 75 line 12—12 of Fig. 11.

Similar reference characters indicate corresponding parts throughout the several figures of the drawings.

Referring, in detail, to the characters of 80 reference marked upon the drawings, the machine includes uprights 12 and 13 which may be mounted upon a base 14 and tied together at their upper portions by means of a horizontally-disposed front plate member 85 15 which serves to support and carry different parts of the machine, as will later be more fully explained.

The main drive shaft 16 is mounted in 90 bearings 17—17 of the uprights and a third bearing 18 which, like the uprights, is also supported upon the before-mentioned base 14. This shaft is provided with driving means, as, for instance, a pulley 19, and also has mounted upon it, intermediate of the 95 bearings 17 and 18, cams 20 and 21, again to be referred to. An eccentric 22 is mounted upon this shaft intermediate of the bearings 17—17, as are also cams 23 and 24, which will later be more fully described. On the 100 end of the shaft is mounted a bevel pinion 25 that meshes with and drives a similar bevel pinion 26 secured on an upwardly-extending diagonally-disposed shaft 27 that is journaled in bearings 28—28 secured to 105 the upright 12. A third pinion 29 is mounted upon the upper end of the shaft 27 and meshes with and drives a fourth pinion 30

secured to a transverse shaft 31 journaled in the upper portion of the uprights 12 and 13.

A third transverse shaft 32 also has its 5 end portions journaled in bearings of the uprights 12 and 13 and serves to carry a drum 33 upon which the fabric is wound after being woven. A ratchet 34 is secured to the drum and is operated by a pawl 35 10 carried upon a rocker-arm 36 journaled upon the shaft 32. One end of a reciprocable connecting rod 37 is pivotedly connected to the outer end of this rocker-arm, the other end being attached to a band 38 which encircles and is carried by the eccentric 15 22 mentioned above.

By this means it will be seen that the drum may be slowly rotated, step by step, through the rotation of the shaft 16, its eccentric 22 and the pawl and ratchet mechanism connected with the drum. In practice these operations are suitably timed so that the fabric is wound upon the drum as it is woven by the action of the weaving mechanism.

The mechanism for handling and laying the warp threads may be similar to that employed in ordinary weaving machines, and, therefore, I have not attempted to show it 30 complete in all respects, but have shown (see Fig. 2) a harness 39 whereby the alternate warp threads are raised and lowered and thus woven around the weft or filling threads in the usual manner. These warp threads (which I will indicate as *a—a*) may 35 be taken from a roll 40 mounted upon a standard 41, said roll adapted to be rotated as the warp threads are drawn therefrom, against the resistance of a weight 42 40 attached to a strap 43 which encircles a reduced part of the roll. 44 represents a reed, such as is commonly employed in weaving machines, to pack the weft or filling threads; and which, in this instance, is carried in the 45 upper ends of vertically-disposed rocker-arms 45—45 hinged to a floor bracket 46, and each carrying a roll 47 for engagement with the cams 23 and 24 mounted upon the before mentioned shaft 16. From this construction, it will be seen that the operation 50 of the cams through their engagement with the rolls of the rocker-arms 45 will cause the latter and their reed 44 to be operated forward and backward to and from the woven fabric with each shifting of the harness, and laying of the filling threads in a way to pack said threads against the warp threads in the usual manner.

The particular type of fabric which the machine is adapted to produce is shown in Fig. 4, and comprises the warp threads *a—a*, two weft threads *b* and *c* successively worked into the warp from opposite sides, the laying of each thread being in double strands—that is, each thread is carried back on it

self within a single shed of the warp, forming a bight or loop projecting from the edge of the warp at one side, and a connecting portion at the other side extending between the laid-in strands, and selvage reinforcing 70 threads *d* and *e* looped or interwoven at each edge with respect to the base and bight or loop ends of the laid-in weft strands.

For this purpose there are provided a pair of transversely reciprocating horizontally-disposed needles 48 and 49 and a pair of vertically reciprocating rotary looper-needle shafts 50 and 51 carrying looper-needle elements, hereinafter more fully referred to. The needles are disposed in horizontally-aligned relation with each other and are secured in diagonally projecting arm-supports 52 and 53 respectively mounted on reciprocating slide rods 54 and 55 slidably supported in suitable bearings or guides 56 and 57 secured to the uprights 12 and 13. At one end, the rods are provided with eared sleeves 58 and 59 pivotally connected by links 60 and 61 to the upper ends of rocker-arms 62 and 63 hinged at their lower ends to floor 90 brackets 64 and 65 and respectively carrying rolls 66 and 67 which engage the grooves of the cams 20 and 21 carried upon the shaft 16.

The weft threads are carried from spools 70 and 71, mounted upon suitable supports 72 and 73 through guide loops 74 provided on the respective arm-supports 52 and 53, to the needle eyes provided at the forward ends of the needles.

The vertically-reciprocating looper-needle shafts 50 and 51 are mounted for vertical sliding and rotary movements in the vertical passages of a pair of bracket supports 75 and 76 secured upon the plate member 15; and at their upper ends are provided with 105 annularly channeled collars 77 and 78 in which rings 79 and 80 are engaged and have trunnion connection with the yoke ends 81 and 82 of levers 83 and 84 pivotally supported upon brackets 85 secured to the inner side of the plate member 15. Rolls 86 and 87 are provided at the inner ends of the levers which engage the grooves of cams 88 and 89 provided upon the shaft 31, and which are designed to impart alternate up-and-down movement to the looper-needle elements. Within pockets 90 and 91, provided in the respective brackets 75 and 76, there are provided gears 92 and 93 keyed upon 110 the looper-needle shafts to permit longitudinal movement of the latter, and engaged by horizontally-disposed rack members 94 and 95 provided at their respective inner ends with yoke portions 96 and 97 embracing the shaft 31, and carrying rolls 98 and 99 engaging the grooves of cams 100 and 101 provided upon the shaft 31, and adapted to reciprocate the racks and, through the gears 92 and 93, to rotate the looper-needle shafts 115 to and fro through a quarter turn.

At the lower ends of the shafts 50 and 51 there are provided flattened looper-needles 102 and 103, shoulderered, as at 104 and 105, to off-set the needle from the shaft as clearly indicated in Figs. 12 and 13, the selvage threads *d* and *e* being carried to the needle eyes from spools 106 and 107 mounted upon suitable supports 108 and 109.

The operation of the machine (Figs. 5 to 10 12) is as follows:

The weft thread *b* carried by the needle 48 is laid in a shed of the warp from the left and is carried beyond the right-hand edge where the looper-needle 103, moving downwardly, is engaged in flat-wise relation between the needle and the strand of the weft at one side, carrying the selvage thread *e* downwardly thereto. The needle 48 then starts its return movement, leaving the 20 thread *b* looped about the looper-needle and the selvage thread *e* carried thereby, and as said needle 48 becomes free of the looper-needle, the latter is rotated a quarter turn (as shown in Figs. 7, 8, and 9), so that a 25 loop opening formed of the selvage thread and the off-set needle is presented in alignment with the needle 49. The needle 49 thereupon moves to the left into the successive shed of the warp passing through such 30 loop of the selvage thread, whereupon the looper-needle 51 is moved upwardly, leaving the selvage thread looped about the needle 49, as indicated in Fig. 10. As the needle 49 reaches its fully projected position (Fig. 35 10), the looper-needle shaft 50 moves downwardly, engaging the looper-needle 102 between the needle and the weft thread *c*, the selvage thread *d* carried by the looper-needle being carried downwardly to form a loop; 40 and thereupon, the needle is retracted (as shown in Fig. 11) and the looper-needle is rotated a quarter turn to present the opening of the loop of the selvage thread *d* to the needle 48 which is then projected through it. 45 As the needle 49 reaches its retracted position, it draws the weft thread *c* back through the loop formed in the selvage thread *e*, which latter is then looped about the double strands of said weft thread. With each 50 operation of the needles, the drum 33 is rotated to feed the warp and wind up the woven fabric; and the harness 39 and reed 44 are operated in the usual manner to alternately raise and depress the warp and compact the weft.

A woven fabric is thus produced in which the weft is formed of two threads fed from opposite sides, and each supplied from a single source of supply, while each selvage 60 is formed by a reinforcing selvage thread looped and interwoven with the end portions of the weft thread, and supplied from a single source of supply, so that the machine may be continuously operated with less attention than is necessary with the usual type

of loom, and without the complication and floor space incident to the shuttles or bobbins heretofore employed to feed the weft. Knitted and reinforcing selvages are produced at each edge by interweaving and 70 looping reinforcing selvage threads with the weft threads; and a tape or braid of symmetrical structure is provided which will withstand pulling strains and wear equally well at each edge. 75

I have illustrated and described a preferred and satisfactory embodiment of the invention, but it will be obvious that changes may be made therein within the spirit and scope thereof, as defined in the appended 80 claims.

Having thus described my invention, what I claim and desire to secure by Letters Patent is:

1. In a fabric weaving machine, warp 85 feeding means, weft feeding means including a weft carrying element adapted to be projected between sheds of the warp, and selvage feeding means including a selvage carrying element adapted to produce loops 90 in such selvage thread through which the weft thread is passed.

2. In a fabric weaving machine, warp 95 feeding means, weft feeding means including a weft carrying element adapted to be projected between sheds of the warp, and selvage feeding means including a selvage thread carrying element adapted to engage such thread in loops in the weft and to produce loops in such selvage thread through which the succeeding weft thread is passed. 100

3. In a fabric weaving machine, warp feeding means, weft feeding means including weft carrying elements at each side of the warp adapted to be projected between 105 sheds of the warp from opposite sides, and selvage feeding means including a selvage carrying element adapted to produce successive loops in such selvage thread through which the respective weft threads are passed. 110

4. In a fabric weaving machine, warp feeding means, weft feeding means including weft carrying elements at each side of the warp adapted to be projected between 115 sheds of the warp from opposite sides, and selvage feeding means at each side of the warp, each including a selvage carrying element adapted to engage such selvage in the projected portions of the weft threads at each side and to form a loop in such selvage threads through which the successive weft thread is adapted to be projected. 120

5. In a fabric weaving machine, warp feeding means, weft feeding means including weft carrying elements at each side of the warp adapted to be respectively projected between successive sheds of the warp from opposite sides, and selvage feeding means at each side of the warp, each including a selvage carrying element adapted 125

to engage such selvage threads through the projected portion of the respective weft threads and to form a loop in such selvage threads, the weft carrying means of the other weft thread adapted to be projected through said loop.

6. In a fabric weaving machine, warp feeding means, weft feeding means including a weft carrying element adapted to be projected between sheds of the warp and retracted to lay double strands of weft thread having a bight at one edge, and selvage feeding means adapted to engage within said bight whereby a selvage thread is woven in looped relation therewith.

7. In a fabric weaving machine, warp feeding means, weft feeding means including weft carrying elements adapted to be projected between sheds of the warp from opposite sides to alternately lay double strands of weft threads from opposite sides having bights at the respective projected ends, and selvage feeding means at each side of the warp, each including a selvage carrying element adapted to engage within said bights to feed selvage threads therethrough and to form loops in such selvage threads through which the double strands of the other weft thread are passed.

8. In a fabric weaving machine, warp feeding means, weft feeding means including a pair of weft carrying needles disposed in horizontal relation, one at each side of the warp, and each adapted to carry a weft thread, means for alternately reciprocating said needles through the sheds of the warp whereby the weft threads are alternately laid from opposite sides, and selvage feeding means adapted to engage the weft threads upon projection between the warp sheds and to form a loop in such selvage thread through which the other weft thread is adapted to be passed.

9. In a fabric weaving machine, warp feeding means, weft feeding means including a reciprocating needle, thread supply means from which a weft thread is adapted to be continuously supplied to said needle, means for reciprocating said needle through the shed of the warp, and selvage feeding means including a selvage carrying element adapted to produce loops in such selvage thread through which the weft thread is passed.

10. In a fabric weaving machine, warp feeding means, weft feeding means including a weft carrying element adapted to be projected between sheds of the warp, and

selvage feeding means including a vertically reciprocating looper-needle element 60 adapted to be engaged and disengaged with said weft whereby a selvage thread is looped in respect to said weft thread.

11. In a fabric weaving machine, warp feeding means, weft feeding means including a weft carrying element adapted to be projected between sheds of the warp, and selvage feeding means including a vertically reciprocating looper-needle element adapted to be engaged through the loop of the weft 70 thread and to produce a loop in such selvage thread through which the successive weft thread is passed.

12. In a fabric weaving machine, warp feeding means, weft feeding means including a weft carrying element at each side of the warp adapted to be projected between sheds of the warp from opposite sides, and selvage feeding means including a pair of vertically reciprocating looper-needle elements 80 adapted to alternately reciprocate into and out of engagement with the weft, to engage such selvage threads with the weft thread at each side, and to produce a loop in such selvage thread through which 85 the successive weft threads are passed.

13. In a fabric weaving machine, warp feeding means, weft feeding means including a weft carrying element adapted to be projected between sheds of the warp, a selvage feeding means including a selvage carrying element, thread supply means from which a selvage thread is adapted to be continuously supplied to said element, and means for reciprocating said element in respect to the projected weft threads whereby 95 such selvage thread is interwoven therewith.

14. In a fabric weaving machine, warp feeding means, weft feeding means including weft carrying elements at each side of the warp adapted to be projected between 100 sheds of the warp from opposite sides, and selvage feeding means including a pair of vertically reciprocating and rotatable 105 looper-needle elements adapted to be alternately reciprocated into and out of engagement with the weft, to engage the projected portion of each weft thread, and rotated to form a loop in such selvage threads for the passage therethrough of the other weft 110 thread.

Signed at Bridgeport, in the county of Fairfield and State of Connecticut, this 26th day of May, A. D. 1926.

JOHN E. FEFEL.
